[57] ABSTRACT

A variable capacitor forming part of an attenuator section includes a rotatable ceramic disc having a metalized configuration on its upper side which may be mutually juxtaposed with respect to a pair of metalized portions on a ceramic substrate therebelow. The metalized ceramic disc is superimposed by a rotatable plastic body engageable for rotating the disc and having an extension depending through an aperture in the substrate to provide an axis portion for the combined rotatable member. A spring is interposed between a grounded metal cover and a portion of the plastic body, urging the ceramic disc toward the substrate.

VARIABLE CAPACITOR INCLUDING A ROTATABLE DIELECTRIC DISC

CROSS-REFERENCE TO RELATED APPLICATION

This application is a continuation-in-part of my application Ser. No. 830,071, filed June 3, 1969, now U.S. Pat. No. 3,622,919, entitled "Step Attenuator of Low Inductance and High Bandwidth" which is assigned to the assignee of the present invention.

BACKGROUND OF THE INVENTION

Use of variable capacitors is frequently desired in tuning circuits, attenuation circuits, and the like, but often tend to be complex in construction, rendering the same difficult to realize in miniature applications. For example, since a variable capacitor conventionally has a movable plate means of some kind, a contact must ordinarily be provided for making a continuous connection to such movable plate means. While fairly heavy bearings can make a suitable connection in the case of fairly large sized variable capacitors, a small frictional contact may suffice in a miniaturized version, leading to a high resistance connection and contact noise. Alternatively, a permanent connection may be made which is subject to flexing failure.

SUMMARY OF THE INVENTION

According to the present invention, a variable capacitor device comprises a fixed member and a movable member wherein the fixed member is provided with a pair of conducting layers forming fixed plates of the capacitor. The movable member has a conducting layer for providing a second or variable plate of the capacitor, with this movable member layer having a configuration for variable mutual juxtaposition with the fixed member conducting layers as the movable member is rotated with respect to the fixed member. Means make electrical connection with each of the pair of fixed member layers while the movable member's conductive layer is electrically floating. A variable capacitance is thereby provided as between the fixed member layers, without necessity for connection to the movable member layer.

The capacitor device according to the present invention advantageously forms part of a miniaturized attenuator section of the type set forth in my above-mentioned application, rendering the use of a large number of such attenuator sections more efficacious in an attenuation selection system.

It is an object of the present invention to provide an improved variable capacitor device having no frictional or other electrical connections between variable and fixed parts.

It is another object of the present invention to provide an improved variable capacitor device adaptable for miniaturized construction and which does not introduce moving contact noise or the like.

It is another object of the present invention to provide an improved variable capacitor device characterized by long and dependable operation in a miniaturized construction, despite the presence of moving parts.

It is another object of the present invention to provide an improved attenuator section adapted for miniaturized construction which is dependable in

operation and which includes a variable capacitor means adjustment.

It is a further object of the present invention to provide an improved variable capacitor means which is simple and economical in construction, and dependable in operation.

The subject matter which I regard as my invention is particularly pointed out and distinctly claimed in the concluding portion of this specification. The invention, however, both as to organization and method of operation, together with further advantages and objects thereof, may best be understood by reference to the following description taken in connection with the accompanying drawings wherein like reference characters refer to like elements.

DRAWINGS

FIG. 1 is a plan view of an attenuator section according to the present invention;

FIG. 2 is a side elevational view of the FIG. 1 attenuator section with parts thereof broken away and illustrating the construction of variable capacitor devices according to the present invention;

FIG. 3 is a partially schematic view showing the relative positions of electrical components and ground contact points in the aforementioned attenuator section;

FIG. 4 is a more fully schematic diagram of the electrical circuit of the above-mentioned attenuator section;

FIG. 5 is a top view of a ceramic substrate forming part of the attenuator section and variable capacitor devices according to the present invention;

FIG. 6 is a bottom view of the FIG. 5 ceramic substrate;

FIG. 7 is a top view of a ceramic disc forming part of a capacitor device according to the present invention;

FIG. 8 is an edge view of the FIG. 7 disc;

FIG. 9 is a side view of an insulating body for providing means for mounting the FIG. 7 disc for rotational motion, and engaging means for bringing about such rotation;

FIG. 10 is a top view of the FIG. 9 body; and

FIG. 11 is a combined movable member according to the present invention including the FIG. 7 disc and the body of FIG. 9 for rotating the same.

DETAILED DESCRIPTION

Referring to FIGS. 1 through 4, illustrating a capacitor device according to the present invention and an attenuator section including the same, such attenuator section comprises a ceramic strip or substrate 10 which is soldered or otherwise bonded to a grounded metal clip member or cover 12. A pair of voltage divider resistors 14 and 16, connected in series between an input contact 18 and grounded cover 12, are formed of resistance material on the bottom of the ceramic strip. The common terminal of such voltage divider is connected to an output contact 20. Both of the contacts 18 and 20 are insulatingly mounted on the metal cover by sleeves 22, suitably formed of plastic material, through which shafts of the contacts extend to the ceramic substrate 10 where connections are made from the contact shafts to circuitry on the bottom of the substrate.

The resistive coatings forming resistors 14 and 16 are more particularly illustrated in FIG. 6 wherein the coat-

ing indicated at 14 connects between conductive metalized land 76, soldered to the shaft of input terminal 18, and conductive metalized land 78, soldered to the shaft of output terminal 20. Also, resistive coating 16 is disposed between land 78 and land 80 which is soldered to a depending portion of grounded metal cover 12. Resistive and conductive coatings are adhered to the ceramic in a conventional manner.

A variable input capacitor 24 is formed integrally with the ceramic substrate, with metalized portions of the substrate providing conductors forming a fixed part of capacitor 24. A partially metalized ceramic disc 26 forms a movable member of capacitor 24, such disc being rotatable by a slotted adjustment member or body 28 secured to the disc. Body 28 is biased for urging disc 26 toward substrate 10 by a spring 40 disposed between a shoulder 42 of body 28 and the underside of cover 12. Body 28 suitably extends through a coaxial aperture in cover 12 and is conveniently provided on its upper end with a diametrically extending slot 43 engageable with a screwdriver or the like by means of which body 28, and consequently disc 26, may be rotated.

The input capacitor 24 is connected between input contact 18 and grounded cover 12. A variable coupling capacitor 30 is also formed integrally with the ceramic substrate and is connected between input contact 18 and one terminal of a damping resistor 32. The damping resistor is provided as a resistive coating on the top of the ceramic substrate 10, as illustrated in FIG. 5, and has its other terminal connected to output contact 20 at the common junction of the voltage divider resistors. The damping resistor prevents "ringing" by damping signal oscillations without materially attenuating the signal transmitted through the voltage divider resistors. Such a damping resistor typically has a value much lower in resistance than that of the voltage divider resistors. As is well understood by those skilled in the art, the voltage divider resistors will have different values dependent upon the attenuation desired.

A shunt capacitor 34 may be employed in the attenuator section, and is connected between ground and the common terminal of coupling capacitor 30 and damping resistor 32. Two grounding fingers 35, extending from the sides of cover 12, connect the capacitor 34 to ground. The capacitors 30 and 34 provide an AC voltage divider while resistors 14 and 16 provide a DC voltage divider for the signal being attenuated. The capacitors will have values selected for maintaining proper circuit constants as well understood by those skilled in the art. Input capacitor 24 is adjusted to provide each attenuator section with the same input capacitance and compensates for the changes in the values of capacitors 30 and 34 with changing attenuation, as well as for other capacitance which may be present.

A plurality of attenuator sections as described herein are mounted peripherally on a drum in the attenuator apparatus according to the aforementioned application, such that the attenuator sections are individually selectable with rotation of the drum, different of the attenuators providing differing attenuation. An attenuator section is connected when its input and output contacts 18 and 20 meet fixed contacts, not shown herein. Four ground contacts 36 engage the metal cover 12 for

grounding the same in a manner achieving low inductance and a wide bandwidth as further set forth in the above referenced application. The attenuator sections are mounted within slots in the aforementioned drum, with side flanges 38 engaging portions of such drum.

According to a feature of the present invention, capacitors 24 and 30 are constructed such that no connection is made to the metalized ceramic disc 26, but rather the same is electrically floating, while being adapted for variable capacitive relation with metalized portions on ceramic substrate 10. A moving contact is eliminated, with attendant problems related to maintaining a low resistance connection, and noise related to movement of such contact. Referring particularly to FIG. 7, illustrating the planar ceramic disc 26 forming a movable member of a capacitor in accordance with the present invention, this disc has adhered thereto a pair of flat surfaced conductors 44 in the form of metalized portions or conductive coatings, suitably substantially semicircular in configuration, being insulated from one another, and each lying on one side of a central aperture 46 in disc 26. The conductive coating or coatings form movable capacitor plates. Although two such flat surfaced conductors are illustrated, one of the conductive configurations 44 is sufficient for providing the desired capacitance in instances where the attenuation constants indicate a smaller capacitance is suitable. 30 Metallized coating is applied to the ceramic disc in a conventional manner.

A fixed member of the variable capacitor according to the present invention is provided by the ceramic substrate 10 upon which are disposed metalized portions or conductive coatings forming flat surfaced conductors for juxtaposition with the coating on disc 26. These coatings provide fixed capacitor plates. Referring to FIG. 5, for example, a pair of flat surfaced conductors for capacitor 24, disposed in the same plane on substrate 10, are numbered 48 and 50. A first metal coating 48 provides a flat surfaced conductor disposed at one end of ceramic substrate 10 on the upper side thereof and makes connection with a depending portion of metal cover 12 by means of soldering. The first metal coating 48 is entirely on one side of an aperture 52 which is slightly larger than aperture 46 in disc 26. On the opposite side of aperture 52, a metal coating 50, insulated from coating 48 by the substrate, provides a second flat surfaced conductor for the fixed capacitor member. Conductor 50 is here substantially semicircular in configuration and suitably matches one of the metal coatings 44 on disc 26. It also forms an integral part of metalized conductor 54 extending along the upper surface of substrate 10 for making connection with terminal 18, the shaft of which will extend through aperture 56 where the two may be soldered together.

To provide the desired capacitive relation, disc 26 is disposed above substrate 10 with aperture 46 aligned with aperture 52, and with the metal coating 44 on disc 26 disposed upward or away from coatings 48 and 50. Thus, disc 26 provides insulated spacing for the capacitor. It will be seen that if one of the metal coatings 44 is substantially entirely juxtaposed with respect to coating 48, while the other coating 44 is substantially juxtaposed with respect to coating 50, capacitor 24 will provide minimum capacitance as between coatings 48

and 50. If, however, disc 26 is rotated by 90° in either direction, a substantially maximum capacitance is achieved, wherein coatings 44 provide a bridge therebetween. Any degree of capacitive adjustment between the two extremes can be provided without need of making connection to the conductive coating or the coatings on the movable element. The capacitance range can be changed by selection of a differing thickness for disc 26, enlarging or contracting the size of the disc and/or the conductive layer, placing one or both of the fixed coatings on the opposite side of the substrate, or the like.

Further considering FIGS. 9 through 11, these figures illustrate means for mounting the disc 26 for rotational motion with respect to the fixed member, and means for engaging the same for rotation, in the form of plastic body 28, is suitably adhered to the top surface of disc 26. Body 28 is desirably adhered to ceramic disc 26 over the conductive layer or layers 44. The body 28, which is suitably formed of an insulating plastic material having a low dielectric constant, and having rigid mechanical characteristics, extends through central aperture 46 in disc 26 to provide a lower axis portion 58 for the movable member. This axis portion has an outside diameter adapted to be received in bearing relation through aperture 52 in substrate 10. Plastic body 28 is illustrated by itself in FIGS. 9 and 10, and is illustrated as secured to disc 26 in FIG. 11. The body 28 includes a lower cylindrical portion 60 having a diameter substantially matching that of disc 26, and an upper smaller diameter portion 62 provided with the engageable slot 43 by means of which the body is turned for varying the capacitance. Therebetween, body 28 is provided with a shoulder 64 of intermediate diameter, around which spring 40 is received for bearing upon the lower portion 60 as illustrated in FIG. 2 which shows the assembled capacitor. The capacitor plate spacing is maintained by the spring bias thus applied. The body 28 and disc 26 are adhered by conventional methods so as to form a substantially unitary member.

Referring to FIG. 5, conductive layer 54 to the right of aperture 56 terminates in a first flat surfaced conductor 66 of capacitor 30, while a second, coplanar, flat surfaced conductor 68 is provided by part of a similar metal coating 70, insulated from the first, and extending to the right for making connection with the resistive coating which forms resistor 32. Resistor 32 is located between coating 70 and metalized land 72 adapted for connection by means of soldering to the shaft of output terminal 20.

Capacitor 30 is further provided with a central aperture 74 in substrate 10 adapted to receive the axis portion 58 of a capacitor movable member as illustrated in FIGS. 9 through 11. It will be observed that each of the flat surfaced conductors 66 and 68 are quarter-circular in this instance, and consequently a ceramic disc 26 forming part of the movable member need have only one conductive coating 44 applied thereto for aligned juxtaposition with metal coatings 66 and 68, in the maximum capacity position of the capacitor. In this

connection, it should be noted the fixed conductor configurations illustrated herein for capacitors 24 and 30 are only two alternatives, with other variations in configuration being possible for providing requisite low and high capacitance conditions of maximized and minimized mutual juxtaposition of the fixed and movable conductor surfaces.

While I have shown and described preferred embodiments of my invention, it will be apparent to those skilled in the art that many changes and modifications may be made without departing from my invention in its broader aspects. I therefore intend the appended claims to cover all such changes and modifications as fall within the true spirit and scope of my invention.

I claim:

1. A variable capacitor device comprising:
a fixed capacitive member including an insulating substrate with a first pair of conducting layers adhered thereon;
a movable capacitive member including a disc of insulating material having a second pair of conducting layers adhered thereon;
means for axially mounting said movable member for rotation with respect to said fixed member so that said disc provides spacing between said first pair of conducting layers and said second pair of conducting layers;
engaging means for bringing about said rotation including an insulating body movable with said disc and extending through the center of said disc to provide an axis portion for said movable member and forming part of the means for mounting said movable member for rotation, said body having an engagable portion for rotating the same;
means for urging said fixed and movable capacitive members toward one another during rotational movement of said movable member;
said second pair of conducting layers having configurations adaptable for variable juxtaposition above said fixed member so that the movable member provides variable capacitive coupling between said first pair of conducting layers during said rotational movement.
2. The device according to claim 1 wherein the adhered conducting layers on said disc are substantially semicircular.
3. The device according to claim 1 further including a cover having an aperture providing access to said body substantially coaxial with said axis portion,
said means for urging said members together comprising a spring disposed between said cover and a shoulder provided on said insulating body above the conductor adhered to the movable member.
4. The device according to claim 1 wherein said fixed member is provided with an aperture for receiving the axis portion provided by said body, and further forming part of said means for mounting said movable member for rotational motion.
5. The device according to claim 1 wherein said body is formed of plastic.
